UNITED STATES PATENT OFFICE.

OTTO GÜNTHER, OF ESSLINGEN, GERMANY, ASSIGNOR TO THE SUPERHEATER COMPANY, OF NEW YORK, N. Y., A CORPORATION OF DELAWARE.

FEED-CONTROL APPARATUS FOR STEAM BOILERS.

Application filed May 31, 1923. Serial No. 642,404.

To all whom it may concern:

Be it known that I, Otto GÜNTHER, a citizen of Germany, residing at Esslingen, Wurtemberg, Germany, have invented certain new and useful Improvements in Feed Control Apparatus for Steam Boilers, of which the following is a specification.

This invention relates to water feed apparatus for delivering water to steam boilers in such a manner as to permit the feed water to be delivered either into the steam space above the water level, or into the water space below the water level of the boiler.

The construction and operation of my invention may be better understood by considering the varying conditions under which water may be fed into the boiler of a power plant, such as, for example, a locomotive engine.

When a locomotive boiler is steaming freely, or when, by reason of operative conditions, such as favorable grades, standing at stations, blowing off steam at the safety valve, or in any case in which heavy demands for steam are not being made upon the boiler, it is desirable to deliver the feed water into the steam space; as, for instance, into the steam dome, or other convenient place above the water line. This delivery of the feed water causes the water to become directly heated by the steam, and to mingle with the water already in the boiler without such a difference in temperature as to produce objectionable effects, such as contraction stresses, inequality of material temperatures, and the like, tending to cause leaks and other disturbances.

When, however, the boiler is subjected to such demands for power-development in the cylinders as to render it inadvisable to abstract heat directly from the steam by the incoming feed water, it may be preferred to deliver the feed water into the boiler below the water line instead of into the steam space.

My invention consists of an improved feed water head provided with separate water outlets and containing valves and operating mechanism by means of which the feed water may be directed either into the steam space or into the water space of the boiler. This control of the direction of the water is made automatically by the variations of the steam pressure in any desired portion of the engine, although I may provide additional

mechanism by which it may be effected also by manual operation.

The operation of the mechanism in my invention may be either direct or indirect, as may be preferred.

In the accompanying drawings, which illustrate an example of my invention without defining its limits, Fig. 1 is a vertical section, taken on the line A—B—C—D—E of Fig. 4, of the feed head as designed for indirect control, and showing the operative position of the main control valve members for permitting the feed water to pass to the steam space of the boiler; Fig. 2 is a view similar to Fig. 1 showing a different operative position of the main control valve for permitting the feed water to flow to the water space of the boiler; Fig. 3 is a front elevation of the feed head, one half thereof being broken away; Fig. 4 is a section on the line 4—4 of Fig. 1; Fig. 5 is a section on the line 5—5 of Fig. 8 showing the feed head in position on a boiler; Fig. 6 is a vertical section of a modification showing a direct-operated head, the parts being shown in position to feed the water to the water space; Fig. 7 is a view similar to Fig. 6, showing the parts in position to feed to the steam space; and Fig. 8 is a side elevation (somewhat diagrammatic) of a locomotive showing an installation of the invention thereon.

The horizontal cross-section, Fig. 4, shows the parts of the indirect control feed head grouped as actually constructed to secure compactness. The vertical sections, Figs. 1 and 2, show the parts opened out as if the path A—B—C—D—E of the vertical section were straightened out, so as to avoid conflict or superposition of the various parts and to enable the construction to be more clearly shown.

Since it is desirable that more than one feed water supply be provided in locomotive practice, the apparatus as shown is designed to permit the use of two independent feed sources, one a feed pump, as shown at 41 in Fig. 8, shown as delivering through a feed water heater 46, and the other an injector, shown at 42, Fig. 8, in the cab of the locomotive.

Referring to Figs. 1 to 5 inclusive and to Fig. 8, feed water is delivered to the feed head H through either of the pipes 1 or 2 by the feed pump 41 or injector 42 respectively, according to which feed supply is to be used,

- and passes into the water chamber 5 formed in the lower portion of said head. A pair of one way or check valves 3 and 4 are provided within the head H for controlling the inlets 5 of the pipes 1 and 2 respectively, said valves being adapted to be opened by the pressure of the water passing through their respective pipes and to prevent the flow of water from the water chamber to the pipes.
- 10 As shown in Figs. 1 and 2, a main control valve 6 is mounted within the central portion of the head H for controlling the passage of water from the water chamber 5. This valve is slidably mounted, in suitable bearings provided in the head casing, for vertical movement between a pair of valve seats 15 and 18 and is arranged when in contact with the lower seat 18, as shown in Fig. 1, to shut off communication between the water chamber 5—5 and a passage 7—7 located above said water 20 chamber. When the valve is in the upper position shown in Fig. 2, communication is established between the water chamber 5—5 and the annular passage 8—8 and is shut off between the passage 7—7 and the water 25 chamber 5—5. The establishment of communication between the water chamber 5—5 and the passages 7—7 and 8—8 by means of the main control valve is automatically effected to permit the passage of the feed 30 water to the water or steam space of the boiler by mechanism presently to be described.
- 35 Located immediately below the control valve is a piston 9 provided on its upper face with a double annular seat 10. This piston is slidably mounted within a cylinder 11 connected as by means of the pipe 12 with the steam chest 44 of the locomotive. When the throttle of the locomotive is opened so 40 that steam under pressure is present in the steam chest, the pressure of such steam is communicated through the pipe 12 to the under side of the piston 9, thus causing the piston to move upwardly and force its seat 45 into contact with an annular seat 10^a to cut off communication between the passage 8 and an annular conical passage 13. As the piston 9 moves upwardly its upper face contacts with the lower end of the stem of the 50 main control valve 6 and lifts said valve against the water pressure within the water chamber 5. The upper end of the stem of the valve 6 is formed into a relief valve 14 which is normally held to its seat by the 55 pressure of a spring 21, the valve and spring being mounted within the casing or bonnet 21^a, which is provided with a plurality of apertures 22 opening to the atmosphere. The passage 8—8 extends upwardly at the 60 right in Figs. 1 and 2 and terminates in an 65

annular chamber, the upper wall of which is formed to provide a seat 16^a for the one way valve 16. The seat 16^a is provided with a plurality of holes 23 through which water passes from the passage 8—8 to the outlet 17 70 of the feed head, said outlet having connected thereto a pipe 47 which as shown in Fig. 8 extends downwardly to the water space of the boiler. The passage 7—7 located above the main control valve 6 and the water chamber 5 extends to the left (Fig. 1) and terminates in an annular chamber similar to the termination of the passage 8—8. The upper wall of this annular chamber is formed to provide a valve seat 19^a for a check valve 19 similar to the check valve 16. The upper wall of this annular chamber is provided with a plurality of holes 24 through which the water passes from the chamber 7—7 to the outlet 20 of the feed head, said outlet having connected thereto a pipe 48 which as shown in Fig. 8 of the drawing leads to the steam space. A bleed pipe 27 leading to the atmosphere communicates with the conical passage 13—13. 90

Manually operated valves 28, 29, are preferably provided for closing the outlets 17, 20, of the feed head respectively.

The pipe 12 leading to the steam chest of the engine is preferably provided with a shut-off valve 40, the stem 43 of which is extended to the cab of the locomotive and is provided with a hand wheel 45 by means of which the engine-man may cut off communication of the steam chest with the feed head. It will be observed that the two check valves 16 and 19 respectively, receive the direct water pressure from the water chamber upon only a portion of their areas, but that when the pressure from the water chamber is exerted through the holes 23 on the right, or 24 on the left, an additional annular area under the seats of the valves, at 25 or 26, will receive water pressure and that this additional area under pressure will determine the 110 lifting of the valve which receives it. It will also be seen that whenever the chamber 8 is in communication with the external atmosphere by way of the passage 13 and pipe 27 as shown in Fig. 1, the preponderance of 115 pressure on the upper surface of the check valve 16 from the boiler will tend to hold it down; likewise when the chamber 7 is in communication with the external atmosphere through the relief valve 14 and openings 22, 120 as shown in Fig. 2, the preponderance of pressure on the upper surface of the check valve 19 will tend to hold the said valve 19 down.

The operation of the feed head above described is as follows: The feed water is delivered to the head H by either the pipe 1, if the feed pump is used, or by the pipe 2, if the injector is used, the water in either case being delivered into the chamber 5 from 125

which is may pass into the chamber 7 or 8 according to the position of the control valve 6. When the throttle valve of the engine is opened, the pressure of the steam within the 5 steam chest is communicated through the pipe 12 to the cylinder 11, and acting upon the under side of the piston 9, forces the piston upwardly against the water pressure in the chamber 5 until the double annular 10 seat 10 upon the upper face of the piston contacts with the seat 10^a and shuts off the communication between the passages 8 and 13. This upward movement of the piston 9 also lifts the control valve 6 and the relief 15 valve 14 off their respective seats. The water pressure in the chamber 5 forces the valve 6 upwardly against the seat 15 thus closing the communication between the water chamber 5 and passage 7; the position of the 20 parts being as shown in Fig. 2. The water passes through the holes 23 against the under side of the valve 16, thus lifting the feed valve and permitting the water to flow through the outlet 17 and pipe 47 to the 25 water space of the boiler. In the meantime, the opening of the check valve 14 vents the passage 7 through the openings 22 to the atmosphere and permits the check valve 19 to be closed by the boiler pressure upon its 30 upper face.

When the pressure in the valve chest 44 of the locomotive engine falls, as for example when the throttle valve of the locomotive engine is closed, when the engine is running down hill, or is standing still, or when steam communication between the cylinder 11 and valve chest 44 is cut off by the valve 40, the piston 9 and control valve 6 will be pushed downwardly by the spring 21, the 40 parts then being in the position shown in Fig. 1 of the drawing. With the parts in this position, the double seat 10 of the piston 9 is out of contact with the seat 10^a, thus placing the passages 8 and 13 in communication, and as the passage 13 connects with the atmosphere through the pipe 27, the pressure within these passages is relieved and the valve 16 is forced against its seat 16^a by the boiler pressure. The water pressure in the chamber 5 holds the main control valve 6 firmly against the lower seat 18 and as the valve is out of contact with the upper seat 15, the passage 7 is now in communication with the water chamber. The 50 pressure of the water being communicated through the passage 7 and holes 24 at the underside of the check valve 19 causes said valve to be raised off its seat against the boiler pressure and permits the water to 55 flow through the passage 7 and holes 24 to the outlet 20 of the feed head and thence through the pipe 48 to the steam space of the boiler. It will thus be seen that the control of the direction of the feed water 60 into either the water space or the steam

space of the boiler is governed automatically by the variation of pressure within the pipe 12. Since the variation of pressure within the pipe 12 depends upon the variation of pressure in the valve chest, the delivery of feed water into the boiler is automatically controlled in the most efficient manner, the feed water being delivered into the steam space when the demand for steam for power purposes is light or entirely 70 stopped and into the water space when the steam which is being generated by the boiler is being freely used. If, however, for any purpose, the operator should so desire, the feed may be delivered into the steam space 75 irrespective of the pressure within the pipe 12 by closing the valve 40.

In Figs. 6 and 7, I have shown another form of my invention in which the automatic control of the feed water into the steam or water space is directly operated. As shown a head H' is formed at its upper portion in a cylinder 30 in which a piston 31 is slidably mounted. A valve 32 is suitably connected to said piston, the upper end of 80 said valve being reduced and threaded for the reception of a nut 32^a which serves to clamp the valve to the piston. The lower portion of the valve 32 is in the form of a hollow sleeve, the interior of which communicates with a pipe 34 through which the feed water is delivered to the head. The side walls of the lower sleeve portion of the valve are provided with a plurality of ports 32^b which are adapted to communicate with either the pipe 35 leading to the water space of the boiler, or to the pipe 36 leading to the steam space according to the position of the valve and piston. The cylinder 30 of the head H' is connected as by means of the pipe 33 with the steam chest of the engine. When steam is admitted to the valve chest of the engine by the opening of the engine throttle, pressure of such steam forces the cylinder 31 and valve 32 into the lower position shown in Fig. 6. In this position of the parts, it will be noted that the ports 32^b are in communication with the pipe 35 and the feed water entering the interior of the valve 32 from the pipe 34 will pass through the ports 32^b to the pipe 35 and thence to the water space of the boiler. When the pressure in the pipe 33 is relieved or cut off, the water pressure in the pipe 34 will push the valve 32 and piston 31 into the upper 100 position shown in Fig. 7. In this position of the parts, the ports 32^b are in alignment with the pipe 36, the water then passing 105 through the pipe 36 to the steam space of the boiler.

It will be seen that with an installation constructed in accordance with the principles herein described, I preserve the advantages secured by delivering feed water to the water space, while avoiding the dis- 110 115 120 125 130

advantage of delivering cooler feed water thereto when there is no waste steam available for heating it. It will be understood that when the feed water is delivered into the water space, the delivery will be automatically effected by the apparatus hereinbefore described, and the feed water, at such times, will be delivered to the feed head by the pipe 1 connected with the feed water heater 46. The feed into the steam space permits the advantage of preheating with coincident purification of the feed water when the engine is operating at high boiler efficiency or when the pressure from the steam chest is shut off or when the safety valve is blowing off. This enables heat which would otherwise escape to be utilized, thus avoiding the injurious effects upon the strength and tightness of the boiler produced by feeding thereto water which has not been sufficiently preheated.

The connection of the chambers of the indirectly operated valves (shown in Figs. 1 to 5 inclusive) with the atmosphere, permits any leakage of steam or water past such valves to be observed, while the apparatus is in operation.

While I have shown my invention as applied to a locomotive boiler, it is to be understood that its use is not limited to any particular type of engine or boiler as it will be obvious that the principles of the invention herein described are applicable to the feeding of feed water into the steam space or water space of a steam boiler of any type without regard to the use to which the steam generated is to be applied.

I claim:

1. In a feed water control mechanism for steam boilers, the combination of a housing having an outlet for receiving a connection to the steam space of a boiler, an outlet for receiving a connection to the water space of a boiler and an inlet for receiving a connection from a source of water supply, a pressure member adapted to be actuated by fluid pressure, and means controlled by said pressure member for shutting off the connection between said inlet and either one of said outlets while the connection between said inlet

and the other outlet is open, such means including a two-ported valve which in one position permits the passage of the feed water towards the one outlet and in the other position towards the other outlet.

2. In a feed water control mechanism for steam boilers the combination of a housing having an outlet for receiving a connection to the steam space of a boiler an outlet for receiving a connection to the water space of a boiler and an inlet for receiving a connection from a source of water supply, a valve for closing said steam space outlet, a valve seat therefor having an auxiliary port, a valve for closing said water space outlet, a valve seat therefor having an auxiliary port, a pressure member adapted to be actuated by fluid pressure, a two-ported valve controlled by said pressure member and two seats for such valve, the first mentioned auxiliary port communicating with the aperture in one of such seats, and the other auxiliary port communicating with the aperture in the other of such seats.

3. In a feed water control mechanism for steam boilers the combination of a housing having an outlet for receiving a connection to the steam space of a boiler an outlet for receiving a connection to the water space of a boiler an inlet for receiving a connection from a source of water supply and two relief ports, a valve for closing said first mentioned outlet, a valve seat therefor having an auxiliary port, a valve for closing said other outlet, a valve seat therefor having an auxiliary port, a pressure member adapted to be actuated by fluid pressure, a two-ported valve controlled by said pressure member, two seats for such valve, the first mentioned auxiliary port communicating with the aperture in one of such seats and with one relief port, and the other auxiliary port communicating with the aperture in the other of such seats and with the other relief port, and means for closing such relief ports, such means being actuated by said pressure member.

In testimony whereof I have hereunto set my hand.

OTTO GÜNTHER.
